CLAIM

The ornamental design for a threading tool with pull tab, as shown and described.

DESCRIPTION

FIG. 1 is a perspective view of a threading tool with pull tab, showing a first embodiment of my new design in a closed position;

FIG. 2 is a front elevational view of FIG. 1, the rear elevational view being a mirror image thereof;

FIG. 3 is a top plan view of FIG. 1, the bottom plan view being a mirror image thereof;

FIG. 4 is a rear elevational view of FIG. 1;

FIG. 5 is a front elevational view of FIG. 1;

FIG. 6 is a rear perspective view thereof, illustrated in an open position; FIG. 7 is a front perspective view of FIG. 6; FIG. 8 is a perspective view of a second embodiment in the closed position;

FIG. 9 is a front elevational view of FIG. 8, the rear elevational view being a mirror image thereof;

FIG. 10 is a top plan view of FIG. 8, the bottom plan view being a mirror image thereof;

FIG. 11 is a rear elevational view of FIG. 8;

FIG. 12 is a front elevational view of FIG. 8;

FIG. 13 is a rear perspective view thereof, illustrated in an open position; and,

FIG. 14 is a front perspective view of FIG. 13.

The broken lines showing a logo in the drawings depict environmental subject matter and form no part of the claim. The broken lines shown in FIGS. 6 and 13 depict portions of the threading tool with pull tab which forms no part of the claim.

1 Claim, 8 Drawing Sheets
